UNITED STATES PATENT OFFICE

SCHULIM BRAUNSTEIN AND SEMION MEERSON, OF BERLIN, GERMANY

PROCESS FOR THE GENERATION OF A REFRIGERANT JET FOR DENTAL OPERATIONS

Application filed January 14, 1928, Serial No. 246,892, and in Germany January 15, 1927.

Our invention relates to the generation of a refrigerant jet or stream for dental operations and the like in cases where a local anaesthetic is called for and contemplates the employment as a refrigerant of air or other gas and of liquefied air or the like as a source of cold.

According to our invention we use as a source of cold the cold vapour of liquefied air or gas. These cold vapours are led counter to, and in close proximity to the stream of air or gas to be cooled, such stream being impelled by a blower or the like. We further provide means for effecting and controlling vapourization of the liquefied air or gas, and we achieve this effect by passing warm air through the liquefied air or gas. It is a further feature of our invention that this warm air is tapped from the stream of air on its way to be cooled, there being set up in the container for the liquefied air or gas the necessary excess pressure for impelling the vapour through the cooler.

As is understood, a vehicle for cold in the course of flow is only available for use for dental surgery work if its temperature can be lowered quite gradually down to that required.

Attempts have been made to satisfy requirements, for example with the employment of an oxygen stream cooled by expansion of carbonic acid gas, heating devices being caused to act on the delivery nozzle and being gradually cut out, whereby the temperature of the oxygen stream was lowered to that brought about by the expansion of the carbonic acid gas.

According to our present invention the gradual variations of the temperature of the refrigerant vehicle is brought about by corresponding variation of the quantity of air or gas current entering the container for liquefied air or gas for effecting and regulating the vapourization. The consumption of cooling medium depends on the required degree of cooling so that it is possible to operate more economically than in known processes in which only highly compressed carbonic acid gas is used as a cooling medium, and approximately the same quantity is ex-

pended irrespective of the temperature desired. A further advantage of the invention resides in the feature that the heating devices at the delivery nozzle for the refrigerant vehicle are dispensed with, and that the vapours of the source of cold can be allowed to escape into the air after having passed through the cooling apparatus, without causing any detrimental effects to living beings.

In what follows it is assumed that liquefied air is employed, it being understood that in lieu of liquefied air there may be employed condensed gases which vaporize at low temperatures.

A construction of apparatus for performance of the present process is illustrated diagrammatically in the accompanying drawing.

Referring to the drawing, the air to be used in the form of a refrigerant stream is forced by a turbocompressor A through a pipe a fitted with a valve b into a drying apparatus B in which it is dried and if desired sterilized or disinfected. Moisture withdrawn from the air at B is run off from time to time by opening a run-off cock c. From the apparatus B air passes through the pipe d into the cooling apparatus C in which it is cooled to the desired temperature by means of surface cooling, the cooling operation being effected according to the counter current principle. From C it is led to the point of consumption through a tube e fitted with a cut-off cock f.

The cold vapour used as cooling medium produced by contact of warm with liquefied air in the container D issues through the pipe l into the cooling apparatus C and traverses the same in the direction opposite to the flow of air to be used as a refrigerant, extracting therefrom a large part of its heat and escaping to the atmosphere through the pipe g. A branch i from the pipe d leads to the container D the warm air necessary for vapourizing the liquid air. By means of the valve k the quantity vapourized can be adjusted; depending on the quantity of cooling medium expended, the rate of cooling and the quantity of air used as a refrigerant can be varied in accordance with requirements. Interposed in the pipe l directly beyond the

point where it issues from the container D is a cut-off valve *h* adjustment of which may also serve to regulate the temperature of the air to be used as a refrigerant, but which serves principally to cut off the supply of liquefied air from the atmosphere when the apparatus is out of use.

With the process according to the invention it is possible to cool air at room temperature gradually and at will to the low temperature necessary for anaesthetic purposes. It is to be understood that for the purpose of our invention we may use a stream of oxygen or any equivalent gaseous medium instead of a stream of air as a refrigerant. In the foregoing specification and in the claims hereafter, we have specified air as the most expedient gaseous medium for dental or similar purposes.

What we claim as our invention and desire to secure by Letters Patent of the United States, is:—

1. A process for the generation of a refrigerant stream for dental purposes consisting in impelling a stream of air, subjecting said stream of air to the cooling influence of the vapor of a liquefied gas, and by-passing a part of the stream of air into the liquefied gas to vaporize the same.

2. A process for the generation of a refrigerant stream for dental purposes consisting in impelling a stream of air, subjecting said stream of air to the cooling influence of the vapor of a liquefied gas, and controlling the vaporization of said liquefied gas by passing an uncooled portion of the stream of air therethrough.

3. A process for the generation of a refrigerant stream for dental purposes consisting in impelling a stream of air, and subjecting said stream of air to the cooling influence of the vapor of a liquefied gas, controlling the vaporization of said liquefied gas by passing air therethrough, and branching said last-named air off said first-named stream of air.

4. A process for the generation of a refrigerant stream for dental purposes consisting in impelling a stream of air, subjecting said stream of air to the cooling influence of the vapor of a liquefied gas, vaporizing said liquefied gas by passing an uncooled portion of the stream of air through said liquefied gas, and varying the temperature of said stream of air by accordingly varying the rate of passage of air through said liquefied gas.

5. A process for the generation of a refrigerant stream for dental purposes consisting in impelling a stream of air, drying said stream of air, subjecting said stream of air to the cooling influence of the vapor of a liquefied gas, and diverting a portion of the dried air into the liquefied gas to vaporize the same.

6. A process for the generation of a refrigerant stream for dental purposes consisting in impelling a stream of air, subjecting said stream of air to the cooling influence of the vapor of a liquefied gas, controlling the vaporization of said liquefied gas by passing air therethrough, and branching said last-named air off said first-named stream of air.

7. An apparatus for the generation of a refrigerant stream for dental purposes, comprising in combination, means for impelling a stream of air, a cooling apparatus for said stream of air, a connection between said impelling means and said cooling apparatus, a container for a liquefied gas, and a connection between said container and said cooling apparatus whereby the vapors arising from the liquefied gas in said container are passed through said cooling apparatus in an opposite direction to the flow of air therethrough to extract heat from said stream of air.

7. An apparatus for the generation of a refrigerant stream for dental purposes, comprising in combination, means for impelling a stream of air, a cooling apparatus for said stream of air, a connection between said impelling means and said cooling apparatus, a container for a liquefied gas, and a connection between said container and said cooling apparatus whereby the vapors arising from the liquefied gas in said container are passed through said cooling apparatus in an opposite direction to the flow of air therethrough to extract heat from said stream of air.

8. An apparatus for the generation of a refrigerant stream for dental purposes, comprising in combination, means for impelling a stream of air, a cooling apparatus for said stream of air, a connection between said impelling means and said cooling apparatus, a container for a liquefied gas, a connection between said container and said cooling apparatus whereby the vapors arising from the liquefied gas in said container are passed through said cooling apparatus in an opposite direction to the flow of air therethrough to extract heat from said stream of air, and means for passing through said container a part of the air for the purpose of controlling the vaporization of the liquefied gas in said container.

9. An apparatus for the generation of a refrigerant stream for dental purposes, comprising in combination, means for impelling a stream of air, a cooling apparatus for said stream of air, a connection between said impelling means and said cooling apparatus, a container for a liquefied gas, a connection between said container and said cooling apparatus whereby the vapor arising from the liquefied gas in said container is passed through said cooling apparatus to extract heat from said stream of air, means for passing through said container air for the purpose of controlling the vaporization of the liquefied gas in said container, and means for tapping said last-named air from the stream of air between said impelling means and said cooling apparatus.

10. An apparatus for the generation of a refrigerant stream for dental purposes, comprising in combination, means for impelling a stream of air, an apparatus for drying said stream of air, a cooling apparatus for said stream of air, a connection between said drying apparatus and said cooling apparatus, a container for a liquefied gas, means for di-

verting some of the air into the container to vaporize the liquefied gas therein, and a connection between said container and said cooling apparatus whereby the vapors arising from the liquefied gas in said container are passed through said cooling apparatus in an opposite direction to the flow of air therethrough to extract heat from said stream of air.

10 11. An apparatus for the generation of a refrigerant stream for dental purposes, comprising in combination, means for impelling a stream of air, a device for drying said air, a cooling apparatus for said stream of air, a connection between said drying device and said cooling apparatus, a container for a liquefied gas, a connection between said container and said cooling apparatus whereby the vapor arising from the liquefied gas in said container is passed through said cooling apparatus to extract heat from said stream of air, means for tapping air from said first-named stream of air between said drying device and said cooling apparatus and passing 25 tapped air through the liquefied gas, and means for regulating the passage of the tapped air.
